UNITED STATES PATENT OFFICE.

FRANK MUELLER, OF MILWAUKEE, WISCONSIN.

GRINDING-MILL.

SPECIFICATION forming part of Letters Patent No. 760,907, dated May 24, 1904.

Application filed February 8, 1904. Serial No. 192,598. (No model.)

To all whom it may concern:

Be it known that I, FRANK MUELLER, a citizen of the United States, residing at Milwaukee, in the county of Milwaukee and State of Wisconsin, have invented certain new and useful Improvements in Grinding-Mills; and I do declare the following to be a full, clear, and exact description of the invention, such as will enable others skilled in the art to which it applies to make and use the same.

This invention relates to improvements in grinding-mills for flour and other cereals.

The object of the invention is to provide a mill of this character in which but one grinding-roll is employed, thereby lessening the expense of construction by doing away with considerable gearing and simplifying the entire arrangement of grinding-machines, and thereby decreasing the power necessary to run the same.

A further object is to provide means for adjusting the feed-roll to cause the grain to be ground fine or coarse, as desired.

With these and other objects in view the invention consists of certain novel features of construction, combination, and arrangement of parts, as will be more fully described, and particularly pointed out in the appended claims.

In the accompanying drawings, Figure 1 is a perspective view of a grain, flour, or feed mill embodying the invention. Fig. 2 is a view of the opposite side of the machine to that shown in Fig. 1. Fig. 3 is a vertical longitudinal sectional view. Fig. 4 is a vertical transverse sectional view taken on the line 4-4 of Fig. 3.

Referring more particularly to the drawings, 1 denotes the frame or casing of the machine, in which is arranged a horizontal transversely-disposed grinding-roll 2, the journals 3 of which project through horizontally-disposed slots 4, formed in the side walls of the casing, and are mounted in bearing blocks or boxes 5, which have a sliding engagement with the sides of the casing in guideways 6. The edges of the bearing blocks or boxes 5 are beveled and engage similarly-beveled edges of the guideways 6, whereby said blocks

or boxes are held in sliding engagement with the guideways.

On the front of the machine are fixed laterally-projecting brackets 7, in which are mounted adjusting-screws 8, which are engaged with threaded openings 9 in the bearing blocks or boxes 5, whereby upon screwing said screws in or out the grinding-roll 2 will be moved back and forth. Coiled springs 10 are arranged on the screws 8 between the boxes 5 and the brackets 7, whereby the grinding-roll will be yieldingly held in position to coact with a counter-plate 12, fixed in the back of the casing adjacent to said roll 2.

Immediately in front of the counter-plate 12 is arranged a vertically-reciprocating stamper 13, consisting of a plate having at its ends trunnions 14, which project through vertically-disposed slots 15 in the side walls of the casing. Above the stamper 13 is arranged a horizontal transversely-disposed shaft 16, on each end of which adjacent to the sides of the casing are arranged cams or eccentric disks 17, on which are arranged straps 18, in the lower ends of which are formed apertures to receive the trunnions 14 on the ends of the stamper-plate 13, so that when the shaft 16 is turned the cams 17 will actuate said straps and reciprocate the stamper-plate.

Within the casing 1 above the roll 2 is arranged a hopper 19, in the lower end of which is formed a discharge-opening through which the grain in the hopper may be discharged and directed between the roll and the counter-plate 12. The hopper 19 is supported at its forward edge by forwardly-projecting lugs or fingers 20, which engage the upper edge of the hopper, and on the rear side of the hopper is provided a curved lug or plate 21, which is adapted to engage and rest upon an eccentric surface 22, formed on the shaft 16, so that as said shaft turns the hopper will be agitated or shaken by the engagement of the cam-surface of the shaft with the lug or plate 21, which action will cause the grain to be fed through the discharge-opening in the hopper.

In the forward part of the casing in juxtaposition to the forward side of the grinding-

roll 2 is arranged a cleaning-brush 23, the bristles of which are adapted to engage the surface of the roll and clean or remove from the same all particles of grain or flour which 5 may have adhered thereto. On the surface of the grinding-roll 2 is formed a series of longitudinally-disposed teeth or corrugations 2', and on the counter-plate 12 is arranged a series of diagonally-arranged teeth or corrugations 12', with which the teeth on the roller coact to grind the grain discharged between the same.

On one of the journals of the grinding-roll is secured a belt-pulley 25, which is connected 15 with a belt wheel or pulley 27, fixed on the end of the shaft 16, by which said shaft is driven. Any suitable means (not shown) may be applied to the journals of the roll-shaft to turn the same and to impart motion to the 20 eccentric shaft 16.

In operation the grain to be ground is placed in the hopper and discharged through the feed-opening in the same. It is forced between the grinding-roll 2 and the counter- 25 plate 12 by the stamper 13. By adjusting the screws 8 the roll 2 may be moved toward or from the counter-plate to cause the grain to be ground more or less finely, as may be desired.

30 From the foregoing description, taken in connection with the accompanying drawings, the construction and operation of the invention will be readily understood without requiring a more extended explanation.

35 Various changes in the form, proportion, and the minor details of construction may be resorted to without departing from the principle or sacrificing any of the advantages of this invention.

40 Having thus described my invention, what I claim as new, and desire to secure by Letters Patent, is—

1. In a grinding-mill the combination with a casing, of an adjustable grinding-roll mounted in the same, a counter grinding-plate fixed in said casing and adapted to coact with said grinding-roll, a reciprocating stamper arranged in said casing, means for vertically reciprocating the same, a hopper arranged above 50 said grinding-roll to discharge grain between the roll and said counter-plate, and means whereby said hopper is vibrated to discharge said grain, substantially as described.

2. In a grinding-mill, the combination with

55 a casing having longitudinally-disposed, horizontal slots formed in the side walls of the same, of a grinding-roll having trunnions adapted to pass through said slots, bearing-boxes yieldingly and slidably mounted on the sides of said casing to receive said journals, 60 means whereby said boxes are shifted to adjust said grinding-roll, a counter grinding-plate fixed in said casing to coact with said grinding-roll, a stamper-plate arranged above said grinding-roll, journals formed on the 65 ends of said stamper-plate and adapted to project through slots formed in the sides of said casing, a shaft journaled in the upper end of said casing, cams fixed on said shaft, straps connecting said cams with the journals on 70 said stamper-plate whereby upon the turning of said shaft said stamper-plate will be reciprocated, a hopper arranged in the upper end of said casing and means whereby said hopper is vibrated, substantially as described.

75 3. In a grinding-mill, the combination with a casing having longitudinally-disposed horizontal slots formed in the side walls of the same, of a grinding-roll having trunnions adapted to pass through said slots, bearing-boxes yieldingly and slidably mounted on the sides of said casing to receive said journals, 80 brackets fixed on said casing, adjusting-screws mounted in said brackets and engaging said bearing-boxes, coiled springs arranged between said boxes and said brackets, whereby said boxes are yieldingly and adjustably held in place to support said grinding-roll, a fixed counter grinding-plate arranged in said casing to coact with said grinding-roll, teeth or corrugations formed on said roll and on said counter-plate, a vertically-reciprocating stamper-plate arranged in said 85 casing, an eccentric shaft journaled in said casing, cams fixed on said shaft and connected 90 to said stamper-plate to reciprocate the same, a hopper arranged in said casing and adapted to be engaged by said eccentric shaft to vibrate the same, and means for cleaning said grinding-roll, substantially as described.

95 4. In testimony whereof I have hereunto set my hand in presence of two subscribing witnesses.

100 FRANK MUELLER.
